FRED MACCAONE AND FRANK T. GENTILE, OF BROOKLYN, NEW YORK

HEEL FOR LADIES' SHOES

Application filed June 16, 1930. Serial No. 461,404.

Our invention relates to shoes for women. The object of our invention is to provide

shoe heels for women's shoes, having a triangular shaped strengthening member that is held in a bore formed in the heel, and that will expand by reason of its resilience and form, and remain in the heel regardless of changes in the size of the bore in which the said member rests.

10 A further object is to provide a heel having a rubber lift which is provided with an upwardly extending central portion adapted to rest in the lower end of the triangular shaped strengthening member, to provide a 15 resilient cushion tread.

Referring to the drawing which forms a part of this specification:

Fig. 1 is a vertical sectional view of a heel for a woman's shoe in which is located a 20 strengthening member and cushion member embodying our invention.

Fig. 2 is an elevational side view of the cushion lift element.

Fig. 3 is a plan view of the cushion lift 25 element.

Fig. 4 is a rear view of the cushion lift element.

Fig. 5 is a cross sectional view on line 5—5 of Fig. 1.

30 Fig. 6 is an end view of the triangular strengthening member shown in its expanded condition.

35 10— indicates a heel for a woman's shoe usually made of wood and formed substantially as shown.

40 11— indicates a bore of triangular cross section which extends from the lower end of the heel to near the upper end thereof, formed by a mortising tool in the usual manner.

45 12— indicates a strengthening member hereinafter referred to as a sleeve, and made from spring sheet metal, such as hard rolled brass or sheet iron, and formed to present a triangle as illustrated in Fig. 6.

50 Each corner 13—bends under laterally applied pressure and serves as a spring which exerts a pressure against the inner walls of the bore after the sleeve is inserted therein as illustrated in Figs. 1 and 5 and is held in

the bore by friction and pressure, as will be readily understood.

It has been shown by experience that the wood changes its form sufficiently to release a sleeve which is simply driven into the bore 55 and is not resilient and able to conform to the changes in the form of the wood, but when compressed so that the slot 14— is closed as illustrated in Fig. 5, and then driven snugly into the bore, the sleeve will hold firmly 60 to the wood without other means for securing it thereto.

15— indicates a leather lift which may be nailed to the wood as illustrated, if a leather lift is desired, but we prefer to use a rubber 65 lift.

In Figs. 2, 3, and 4, a rubber lift is illustrated which may be secured to the heel without the use of nails, which are objectionable.

The rubber is moulded to provide a tread 70 portion 16— and a shank portion 17— formed integral.

The tread portion is shaped to conform to the shape of the heel, and the shank portion is formed triangular in shape and slightly 75 greater in cross section than the opening in the sleeve, so that the rubber will be compressed when forced into the lower end of the sleeve as shown. Thus it will be seen that the pressure exerted by the resilient slotted sleeve to hold it securely in the bore is compounded by the pressure of the rubber shank 80 compressed within the sleeve. Cement is applied over the surface 18— to further assist in holding the cushion tread to the heel, as 85 will be readily understood.

The triangular shape of the sleeve serves to prevent the rubber tread from rotating, and to position it on the heel without loss of time.

By combining the parts as above illustrated, a light and strong heel is provided that is cheap to make and very practical.

We claim:

1. A wooden heel having a deep central bore formed irregular in cross section and extending from its lower end to near the upper end thereof, a hollow reinforcing sleeve of resilient metal divided longitudinally and shaped to fit said bore and held therein under 10:

pressure against its wall by the resilient action of the metal, and a resilient cushion lift connected to the lower end of said heel, said lift having a shank portion formed integral and extending into said sleeve.

5 2. A wooden heel having a bore extending from its lower end to near the upper end thereof, a reinforcing sleeve of resilient metal divided longitudinally and compressed to fit into said bore, and a lift having a resilient shank portion compressed to fit into said sleeve.

10 3. A wooden heel having a bore of irregular cross section extending from its lower end to near the upper end thereof, a reinforcing sleeve of resilient metal divided longitudinally and compressed to fit into said bore, and a resilient cushion lift having a shank portion formed integral therewith compressed to fit into said sleeve.

15 20 In testimony whereof we have affixed our signatures.

FRANK T. GENTILE.
